FROZEN CREAM MACHINE

John Parcell, New York, N. Y.

Application December 2, 1936, Serial No. 113,883

5 Claims. (Cl. 259—66)

This invention concerns the machine or apparatus for manufacturing ice cream, frozen custards or the like.

In the past machines and apparatus of this kind, when serving to prepare larger quantities of frozen produce, have been extremely unwieldy and heavy in weight, since they are called upon to answer very stringent hygienic requirements, since they have to be well insulated in order to yield thermal efficiency, and since they have to be rugged and strong in order to stand the strain of a continuous slow drive by a motor.

It has been the object of this invention to improve upon machines or apparatus of the kind in question, reducing their volume on one hand, and their weight on the other hand, so that they can be readily transferred from one location to another, do not require much room, and even may be set up on counters, or the like, as it may be desired.

In spite of such improved departure, the apparatus or machine of my invention even exceeds apparatus of the prior art in respect to hygiene, thermal efficiency, stability, durability, compactness and mechanical strength.

Some of the objects concern various improvements of the mixer or rotor, which serves to agitate the mixture to be frozen, so that it may be evenly frozen. Still other objects concern the arrangement of the freezing compartment proper, the cooling chamber, the motor compartment, and the said chambers and compartments in combination with each other, as it will be better understood from the following exemplary description in the light of the accompanying drawings, in which

Fig. 1 is an elevation of a partly sectioned-away and partly cross-sectioned apparatus or machine of my invention in a partly schematic presentation.

Fig. 2 shows a modification of the stirrer or rotor of the device of my invention.

Fig. 3 shows a detail in a sectioned top view, this section being taken in Fig. 2 indicated by an arrow and the numeral 3.

Similar numerals refer to similar parts throughout the various views.

In the cross-section to the right of Fig. 1, we find numerous applications of heavy sheet metal or tubing, or the like, which are all shown in solid heavy black elevation and cross-section.

In order further to facilitate the understanding of the drawings, sheet materials are not shown in abutment where they are welded or soldered together, but they are shown slightly spaced

apart, and the letters W and S indicate in connection with points, where the sheet materials are sealedly interconnected, a welded or soldered joint respectively, in a preferred execution of the instant invention.

The base 11 of the apparatus of Fig. 1 has the shape of an inverted bell and may preferably be stamped or spun in heavy sheet material. The lower edge thereof is reenforced by a seam beaded around a reenforcing rod 12.

Near the top of the base 11 various contracted steps, like 13 and 14, coact in facilitating the concentric arrangement of the apparatus.

The top shelf 15 of the base is perforated where necessary for interconnecting the top and bottom of the apparatus, e. g., for the bearing 16 surrounding the shaft 17 interconnecting the motor 22 with the stirrer, mixer or rotor 23 in the freezing compartment 24; or the intake of conduit 18 serving for the discharge of the frozen produce, through opening 25 in the side of the base 11, to a valve 26 at the one end of the said conduit 18; or the waste pipe 19, which is opened or closed by a handle 20 rotatably extending through the sides of the base 11, said waste pipe serving to drain the cooling compartment 27 which cylindrically surrounds the freezing compartment 24; or there are perforations for means assembling the top part with the base of the apparatus. The heads of bolts 21 are for instance soldered onto the bottom 38 of the cooling compartment 27, their threaded ends extend through clearance openings in top 15, and are secured from below upon the base by nuts 28.

The freezing compartment 24 comprises the following parts:

The convex bottom 29 of the freezing compartment 24 is suitably perforated to allow the shaft 17 to interconnect therethrough, and also in order to permit discharge into the elbow 31 of the conduit 18, which by way of a nipple 32 and a coupling 33 connects with the dispensing valve 26. The elbow 31 and the bearing 16 are shown in the drawings to be executed in one unit, which is suitably attached by way of a gasket 30 to the convex bottom 29 of the freezing compartment.

The convex bottom 29 is sealed to the cylindrical shell 34 of the freezing compartment 24, an overlapping seam being shown for the purpose, and it may be reenforced by welding, as indicated, in order to provide a permanent seal.

A skirted cover 35 fits snugly over the top of the shell 34, and bolts 36 are suitably fastened upon the shell 34, by rivets for instance, and ex-

tend through clearance openings in the cover 35, so that the wing nuts 37 may be applied to the top of said bolts 36, and screw the cover 35 down tightly onto the can or shell 34 of the freezing compartment 24.

An annular disc 38 is the bottom for the cooling compartment 21, which serves to receive the freezing mixture, e. g., ice. The inner circle of the bottom 38 is flared up into the beaded rim 10 extending down from the freezing compartment 24, and is shown to be connected thereto by soldering. In order to reenforce the freezing compartment 24 in its upright position, I may provide at suitable angular distance the braces 39, which are indicated in the drawings to be soldered to the outside of the freezing compartment 24, as well as to the bottom 38 of the cooling compartment 21, thus rendering the freezing compartment 24 very stable.

The outer rim of the bottom 38 of the cooling compartment 21 is turned down in ring fashion and engages in and is soldered into a fold 41 at the lower end of the cylindrical outer wall 40 of the cooling compartment 21.

The said soldered fold 41 at the bottom of the outer wall 40 of the cooling compartment 21 snugly fits over the top step 14 of the space 11, and concentrically aligns the cooling as well as freezing compartment upon the base. Insulating material 42 may be placed between the bottom 38 of the cooling compartment 21 and the top shelf 15 of base 11, in order to prevent dissipation of heat from the base into the cooling and freezing compartments, and the bolts 21 clamp the cooling and freezing compartment onto the base, so that the whole becomes a very stable unit.

The second step 13 at the bottom of the base 11 fits into an outer shell 43, which cylindrically arises to substantially the same level as the wall 14. Insulating material 44 is accommodated between the said shell and wall for purposes of preventing the entry of heat from the outside upon the inner compartments. The outer shell 43 is suitably fastened upon the step 13, short screws 45 being for instance indicated for that purpose. This does not have to be a tight seal; except, of course, that the insulating material 44 should not fall out at the bottom.

A U-shaped inverted channel 48 extends in a circle at the top and gathers together the upper rims of the wall 40 and the shell 43. Said upper rims may be suitably spaced apart by wooden spacing lugs 47; and thin bolts 48 extend across the inverted channel 48 and hold the upper ends of the wall and shell, and the channel 48 together.

Over this outer insulating wall formed by the parts 40, 43 and 48 loosely extends a cover 48 with a suitable handle 50 at the center thereof.

The bottom of base 11 is further reenforced by a webbed frame 51 which extends thereacross and may be attached thereto triangularly for instance, one of the connecting legs or legs 52 being indicated at the lower right; suitable cushions 53 may extend from the triangular extremities of the web 51, giving to the apparatus or machine the convenience of a 3-point support.

The web frame 51 serves to support the driving motor 22 which may be an electrical motor with a terminal board indicated at 54. The said motor 22 in turn supports, and the frame 51 may also support the reducing unit 55, to the shaft 17 of which the power of motor 22 is transmitted at a reduced speed; said shaft being ar-

ranged vertically. Shaft 17 is extended as an extension 56 substantially throughout the whole height of the freezing compartment 24, and is superimposed by a square as a key at its upper end 57. A sleeve 58 protectively surrounds the extension 56 and may be soldered and/or pipe-threaded into the bearing 16 as indicated. It will be noticed that if the mixer or rotor 23 is lifted out of the freezing compartment 24, the sleeve 58 still protectively surrounds substantially the whole extent of extension 56 so that the contents of the freezing compartment 24 can never reach the shaft 56. The upper end of the sleeve 58 is closed in and fits slidably over the upper end of extension 56, so as to provide a closure 15 and to prevent splashing of the contents of the freezing compartment onto the extension.

The mixer or rotor comprises the hollow sleeve 60 which is closed at its upper end and fits over the square key 57 of the extension 56, so that it is rotatably engaged by said key and will be rotated when motor 22 is in operation.

A scraper arm 63 extends laterally out from one side of the sleeve 60 and serves to scrape the bottom 29 of the freezing compartment. A helix 61 extends around the sleeve 60, and is spacedly provided with lugs 65. These lugs pivotally supporting the scrapers 64 which engage upon the wall 34 of the freezing compartment 24.

The sleeve 60 may be retained in concentric alignment in the apparatus by providing at the lower end thereof, upon the inside, a bearing 66, which engages upon the outside of a neck 67 extending up from the bearing 16. Below the neck 67 I show a horizontal shoulder 68 on the bearing 16 which thrustwise supports the mixer or rotor 23.

The closed upper end 69 of the sleeve 60 may extend through the cover 35 and may there be concentrically supported by a cap 70 which is fastened upon the cover 35.

Instead of engaging the mixer at the top by way of an extension, shaft 16 may also engage directly upon the mixer at the bottom thereof, as illustrated in Fig. 2. Under these circumstances, the shaft 16 extends by way of a stuffing box represented by a stuffing nut 75 and packing material 76 through a bearing 16. A key formation on the shaft 16 extending as a stub into the freezing compartment, is indicated by way of a pin 77 inserted transversely through that top end of shaft 16, and the lower end 78 of the mixer 79 is shaped to engage upon said key.

A dowel or center 80 rotatably supports the upper end of the mixer 79 and may be fastened by way of a flange 81 provided upon such dowel or center, and by way of a threaded extension above and the nut 82, upon the cover 35 of the freezing container. The helix 83 may be integral with the arbor 85 of the mixer, as shown, and may interconnect at the bottom with the bottom scraper 84, as indicated.

The side scrapers 86 may be made of suitable sheet material and are for instance provided with a bead 87 on one side, said bead 87 accommodating a vertical shaft 88. The beaded portion of the side scrapers may be slotted at suitable points 89, where upper lugs 90 and lower lugs 91 hinged-engage upon the shaft 88 so that the side scrapers may swing to and fro thereon.

The lugs, e. g., 91 form suitable extensions of the helix 83, as shown in the cross-section of Fig. 3. We also take from this cross-section that in the lower lugs 91 I prefer to provide slots 92,

instead of holes, for the shaft 88 or whatever the swivels may be, so that there is some play and the side scrapers during rotation may be pressed further out or less out at their bottom ends than at their top ends where they are oscillatably hinged upon the lugs 90. Flat springs 93 mounted upon the lugs 91 may assist in pressing the side scrapers 86 into engagement with the side walls of the freezing compartment.

10 Although I have shown and described my invention in detail, yet I do not wish to be limited thereby, except as the state of the art and the appended claims may require, for it is obvious that various modifications and changes may be 15 made in the form of embodiment of my invention, without departing from the spirit and scope thereof.

What I claim is:

1. In a freezing apparatus, a circular base with 20 a plurality of steps near the top thereof, a circular cooling compartment with a fold extending as a rim from the bottom thereof and fitting over one of said steps, a freezing compartment assembled with and centrally arising in said cooling 25 department, and a circular shell fitting over another one of said steps and forming an insulating compartment around said cooling compartment.

2. In a freezing apparatus, a circular base with 30 a plurality of steps near the top thereof, a circular cooling compartment with a fold extending as a rim from the bottom thereof and fitting over one of said steps, a freezing compartment assembled with and centrally arising in said cooling department, a circular shell fitting over another one of said steps and forming an insulating compartment around said cooling compartment, and an inverted channel engaged over 35

the top of said cooling compartment and said shell, engaging them together and upwardly closing said insulating compartment.

3. In a freezing apparatus, a circular, inverted bell-shaped base, a motor mounted in said base, 5 a vertical shaft centrally arranged in said base and driven by said motor, a step on said base in concentricity with said shaft, a circular freezing and cooling unit adapted to receive a freezing mixture and having a protruding circular bottom 10 rim, and a mixer in said unit driven by said shaft and shaped near its top to engage upon said shaft, a sleeve stationarily mounted in said unit and arising between said shaft and said mixer, said bottom rim on said unit fitting onto and 15 around said step, so that said base and unit are concentrically aligned for a concentric drive of said mixer.

4. In a freezing apparatus, a mixer, side scrapers, lugs on said mixer, and swivels supporting 20 said scrapers on said lugs, some of said swivels allowing a play transverse to the plane of said scrapers in addition to oscillating play of said scrapers on a group of said lugs, in order to facilitate angular adjustment of the scrapers 25 relatively to their vertical extent.

5. In a freezing apparatus, a mixer, side scrapers, lugs on said mixer, swivels supporting 30 said scrapers on said lugs, some of said swivels allowing a play transverse to the plane of said scrapers in addition to oscillating play of said scrapers on a group of said lugs in order to facilitate angular adjustment of the scrapers relatively to their vertical extent, and tension means 35 on said group of lugs pressing said scrapers substantially centrifugally out.

JOHN PARCELL.
